**HOUSING FOR GAS BURNER CONTROL DEVICES
AND THE LIKE**

Floyd J. Bydalek, Milwaukee, Wis., assignor to Baso Inc.,
Milwaukee, Wis., a corporation of Wisconsin

Application July 25, 1956, Serial No. 42,384

Term of patent 14 years

(Cl. D52—1)

FIG. 1.

FIG. 2.

FIG. 3.

Figure 1 is a side elevational view of a housing for gas burner control devices and the like, showing my new design;

Figure 2 is an end elevational view of the housing shown in Figure 1; and

Figure 3 is a top plan view thereof.

The side of the housing opposite the side shown in elevation in Figure 1 and the end thereof opposite the end shown in elevation in Figure 2 are substantially the same in appearance as the side and end shown in said Figures 1 and 2 respectively.

The essential features of the design reside in the portions shown in solid lines.

I claim:
The ornamental design for a housing for gas burner control devices and the like, as shown and described.
